US00D536389S

(12) United States Design Patent (10) Patent No.: US D536,389 S
LeSourd et al. (45) Date of Patent:  Feb. 6, 2007

(54) GAMING SYSTEM LIGHT CANDLE
(75) Inventors: Kehl T. LeSourd, Reno, NV (US);
Kirk A. Tedsen, Reno, NV (US); Eric L. Wagner, Sparks, NV (US);
Christopher D. Carlisle, Reno, NV (US); Michael MacVittie, Las Vegas, NV (US)

(73) Assignee: IGT, Reno, NV (US)
() Term: 14 Years
(21) Appl. No.: 29/253,517
(22) Filed: Feb. 8, 2006

CLAIM

The ornamental design for a gaming system light candle, as shown and described.

DESCRIPTION

This application relates to the following co-pending commonly owned patent applications: "Gaming System Shared Display and Protective Dome," Ser. No. 29/253,516, "Gaming System Dome For a Shared Symbol Display," Ser. No. 29/253,510, "Gaming System Dome For a Shared Symbol Display," Ser. No. 29/253,574, "Gaming System Dome Cap For a Shared Symbol Display," Ser. No. 29/253,518, "Gaming System Dome Cap For a Shared Symbol Display," Ser. No. 29/253,561, "Gaming System Indicators For a Shared Symbol Display," Ser. No. 29/253,508, "Gaming System Light Candle And Indicator For a Shared Symbol Display," Ser. No. 29/253,513, "Gaming System Having a Gaming Machine Display And Spacer Displays For a Shared Symbol Display," Ser. No. 29/253,560, "Gaming System Indicator For a Shared Symbol Display," Ser. No. 29/253,511, "Gaming System Light candle," Ser. No. 29/253,512, and "Gaming System Spacer Assembly For a Shared Symbol Display," Ser. No. 29/253,515.

FIG. 1 is a front perspective view of a light candle of the gaming system of our new design, that portion shown in phantom is not part of the design sought to be patented and is provided for environmental purposes only.

FIG. 2 is a top plan view of the light candle of the gaming system of our new design illustrated in FIG. 1.

FIG. 3 is an elevated left side view of the light candle of the gaming system of our new design illustrated in FIG. 1, the right side being a mirror image thereof, that portion shown in phantom is not part of the design sought to be patented and is provided for environmental purposes only.

FIG. 4 is an elevated front view of the light candle of the gaming system of our new design illustrated in FIG. 1, that portion shown in phantom is not part of the design sought to be patented and is provided for environmental purposes only.

FIG. 5 is an elevated back view of the light candle of the gaming system of our new design illustrated in FIG. 1, that portion shown in phantom is not part of the design sought to be patented and is provided for environmental purposes only.

FIG. 6 is a front perspective view of a light candle of the gaming system of our new design, that portion shown in phantom is not part of the design sought to be patented and is provided for environmental purposes only.

FIG. 7 is a top plan view of the light candle of the gaming system of our new design illustrated in FIG. 6.

FIG. 8 is an elevated left side view of the light candle of the gaming system of our new design illustrated in FIG. 6, the right side being a mirror image thereof, that portion shown in phantom is not part of the design sought to be patented and is provided for environmental purposes only.

FIG. 9 is an elevated front view of the light candle of the gaming system of our new design illustrated in FIG. 6, that portion shown in phantom is not part of the design sought to be patented and is provided for environmental purposes only; and,

FIG. 10 is an elevated back view of the light candle of the gaming system of our new design illustrated in FIG. 6, that portion shown in phantom is not part of the design sought to be patented and is provided for environmental purposes only.
